United States Patent Office

Des. 199,072
Patented Sept. 8, 1964

199,072

BOWL

Herbert R. Lewis, 126 N. Elmwood Ave., Oak Park, Ill.,
assignor of one-half to Leslie O. Read, Chicago, Ill.

Filed June 18, 1962, Ser. No. 70,571

Term of patent 14 years

(Cl. D44—15)

FIG. 1

FIG. 2

FIG. 3

FIG. 4

FIG. 1 is a sectional elevation view of a bowl embodying this invention;

FIG. 2 is a top view of the bowl pictured in FIG. 1;

FIG. 3 is a bottom view of the bowl pictured in FIG. 1; and

FIG. 4 is a perspective view of the bowl pictured in FIG. 1.

The design is characterized by an eccentrically disposed bowl divider rib in axial alignment with the long leg of a supporting T rib on the lower surface, the short leg of the T being disposed under the smaller portion of the divided bowl.

I claim:

The ornamental design for a bowl, as shown and described.
